UNITED STATES PATENT OFFICE.

ROBERT LUCKNER, SR., OF NEW ORLEANS, LOUISIANA.

DESIGN FOR A BANDBOX.

SPECIFICATION forming part of Design No. 13,093, dated July 25, 1882.

Application filed May 15, 1882. Term of patent 3½ years.

To all whom it may concern:

Be it known that I, ROBERT LUCKNER, Sr., a citizen of the United States, residing at New Orleans, in the parish of Orleans and State of Louisiana, have originated and designed a new form of Bandbox, of which the following is a full, clear, and exact description, reference being had to the accompanying drawings, making a part of this specification.

10 Figure 1 represents a perspective view of the box with cover, and Fig. 2 a top view of box without cover.

Heretofore jewelry-boxes have been made with convex sides and ends; but in said cases 15 the sides and ends of the boxes and the rims of their covers were so constructed that when fitted together their outer surfaces and corners presented unbroken vertical lines.

My design consists in a flat top and bottom, 20 having angular corners and convex sides and ends, the sides of the box made to conform thereto, and provided at its base with a raised band to correspond with the projecting rim of the cover thereof.

The letter A designates the bottom of the 25 box, which is made flat and formed with four angular corners and convex sides, around which is secured the lower edge of the encircling band or sides of the box, designated in the drawings by the letter B. The cover C is 30 also flat and of the same contour as the bottom of the box, and its rim corresponds in general appearance with a band which is constructed around the bottom thereof.

I claim as new—

35 The design for a bandbox, consisting of a flat bottom, A, flat cover C, angular corners, and convex sides, the base of the said box being surrounded with a band corresponding with the rim of its cover, substantially as shown. 40

In testimony whereof I hereunto sign my name.

ROBERT LUCKNER, SR.

In presence of—

JNO. E. CRONE,
J. N. MÜLLER.
